UNITED STATES PATENT OFFICE.

FREDERICK K. HABENICHT AND FRANK H. PIETZSCH, OF ST. LOUIS, MISSOURI, AS
SIGNORS TO RAILWAY DEVICES COMPANY, OF ST. LOUIS, MISSOURI, A CORPORA-
TION OF MISSOURI.

TRANSITION ANGLE-COCK HOLDER.

Application filed December 29, 1927. Serial No. 243,351.

Angle cocks heretofore in use have been uniform in design terminating in a hexagonal head or wrench-hold threaded to receive the end of the train pipe to which it is attached. In order to prevent the loss of the angle cock railway cars are usually provided with angle cock holders engaging with the hexagonal heads. At the present time a new type of angle cock is coming into use which differs from the old in being provided with an auxiliary head projecting to the rear of the main head with an annular groove formed between the two. It is the theory that the use of a U-bolt engaging with this groove will obviate the necessity of angle cock holders. We have found, however, that the necessary clearance between the train pipe and the unthreaded auxiliary head prevents the effective clamping of the pipe by the U-bolt, which is an important feature of such holders so that they may not only prevent the loss of the angle cock when broken from the train pipe but also reduce the liability of such breakage. Thus the desirable functions of an angle cock holder are only partially secured in the new form of cock. Furthermore, the necessity of replacement from stock on hand may at any time require the substitution of an angle cock of the old form for one of the new or vice versa, and hence it is highly desirable to provide all cars with holders which are equally applicable to both forms.

It is the object of our invention to provide a transitional type of holder which will cooperate with the new or old form of angle cock and which will in either case form an effective pipe clamp, and, further one which will not require any longitudinal change in the position of the cock when substitution of one form for the other is made while at the same time providing for the necessary adjustment for slight variation in the length of the train pipe.

In the accompanying drawings, which illustrate one form of angle cock holder made in accordance with our invention, Figure 1 is a side view partly in elevation and partly in section showing our holder applied to an angle cock of the old type; Figure 2 is a similar view showing it applied to an angle cock of the new type; and Figure 3 is a section taken on the line 3—3 of Figure 2.

The body of the angle cock indicated at 5

is provided in both the old form, shown in Figure 1, and the new form, shown in Figure 2, with a hexagonal head 6 which engages with the threaded end of train pipe 7. In the old form this head forms the rear termination of the cock, while in the new form an auxiliary head 8 projects to the rear of the main head, the two heads being separated by an annular groove 9.

Our holder comprises two separable members each provided at its forward end with a part 10 substantially semi-hexagonal in cross section, the two parts cooperating to form a head pocket and each provided with a lip 11 engaging with the front face of the head 6 to prevent the forward movement of the cock. The pocket formed by the parts 10 is divided into two sections by an inwardly projecting ridge 12. The front section of the pocket receives the main head 6 when applied to either form of cock. The rear section performs no function when applied to the old form but receives the auxiliary head 8 when applied to the new form. In addition to forming a shoulder to prevent the rearward movement of the cock, the ridge 12 serves as a reinforcing rib to strengthen the long double pocket which would otherwise have to be of greater thickness to afford the necessary rigidity. At the rear of the pocket the members of the holder are reduced to form approximately semi-circular parts 13 which embrace and firmly clamp the train pipe. These parts 13 terminate in flanges 14 flush with the periphery of the pocket. Formed between the flanges 14 and the rear end of the pocket is a wide annular groove to receive the U-bolt 15 by means of which the holder is secured to the supporting plate 16 which bears against one face of the pocket and one of the flanges 14. Nuts 17 threaded on the ends of the bolt hold the device in position and the bolt ends are preferably split, as shown at 18, to form nut locking means. The wide groove in which the bolt is situated allows for adjustment to compensate for variations in the length of the pipe. It will be understood that the supporting plate 16 may be secured to the car in any well known way.

Having fully described our invention, what we claim as new and desire to secure by Letters Patent of the United States is:

1. An angle cock holder adapted to receive

an angle cock having either a single or a double head, said holder comprising two compartments spaced from each other and being provided with a rib positioned to project into the space between the heads of a double headed angle cock.

2. An angle cock holder having a pocket divided into two parts by an inwardly projecting reinforcing rib and adapted to receive and hold an angle cock having either a single or double head, a supporting plate, a train pipe clamping part at the rear of said pocket and provided with a groove, and a U-bolt in said groove for securing the holder 15 to the plate, said groove being of greater

width than the bolt to provide longitudinal adjustment.

3. A transitional angle cock holder having a pocket adapted to receive the head of a double headed angle cock, the forward part of 20 said pocket being spaced from the rear part and adapted to receive and hold the head of a single headed angle cock, and means for securing the holder in position on a car.

In testimony whereof, we hereunto affix 25 our signatures, this 24th day of December, 1927.

FREDERICK K. HABENICHT.
FRANK H. PIETZSCH.
